COMPRESSED GAS RELEASE

Harry N. Rider, Youngstown, Ohio, assignor to
 "Automatic" Sprinkler Company of America,
 Youngstown, Ohio, a corporation of Delaware

Application December 24, 1941, Serial No. 424,265

6 Claims. (CL. 169—9)

This invention relates to a mechanism adapted to release compressed gases and more particularly to such a mechanism adapted to operate in conjunction with conventional compressed gas cylinders so as to cause the compressed gases therein to be released therefrom, the particular adaptation of the compressed gas release comprising an association with a pressure tank sprinkler system wherein the compressed gases released from the compressed gas cylinders by the compressed gas release mechanism serve to apply pressure to fluid in the pressure tank.

The principal object of the invention is the provision of a compressed gas release mechanism capable upon actuation, of releasing compressed gases from compressed gas cylinders.

A further object of the invention is the provision of a compressed gas mechanism adapted to release compressed gases from compressed gas cylinders and simultaneously cause a signal to be given to indicate the release of the gases.

A still further object of the invention is the provision of a compressed gas release mechanism so designed as to be actuated upon a decrease of air pressure comprising a pneumatic impulse originated by a suction chamber associated with a fluid filled sprinkler system.

The compressed gas release mechanism shown and described herein is adapted to be used with and actually forms a part of a pressure tank sprinkler system which system is disclosed in my Patent #2,277,873 of March 31, 1942, on Pressure tank sprinkler systems. The compressed gas release mechanism shown and described herein comprises in part the subject matter of Patent #2,099,069 of November 16, 1937, to E. A. Lowe et al., wherein a pressure responsive weight releasing mechanism is adequately set forth as to its complete structure and operating principles, which pressure responsive weight releasing mechanism is incorporated in and forms a part of the compressed gas release mechanism herein disclosed. In order to simplify the present disclosure, the pressure responsive weight releasing mechanism is not herein described, or illustrated as it is well-known in the art.

With the foregoing and other objects in view which will appear as the description proceeds, the invention resides in the combination and arrangements of parts and in the details of construction hereinafter described and claimed, it being understood that changes in the precise embodiment of the invention herein disclosed, can be made within the scope of what is claimed

without departing from the spirit of the invention.

The invention is illustrated in the accompanying drawings, wherein:

5 Figure 1 is a side elevation, with parts in cross-section on the line 1—1 of Figure 2, showing the compressed gas release mechanism in operative association with a compressed gas cylinder.

10 Figure 2 is a front elevation with parts broken away showing the compressed gas release mechanism illustrated in Figure 1. Section line 1—1 in Figure 2 indicates the position of the cross-section shown in Figure 1.

15 Figure 3 is a cross-sectional elevation taken on lines 3—3 of Figure 1 and shows in detail a portion of the release latch thereof.

20 Figure 4 is a cross-sectional side elevation similar to Figure 1, showing a modified form of compressed gas release.

25 Figure 5 is a front elevation with parts broken away showing a modified form of the invention wherein a solenoid replaces the pneumatic release. Figure 5 is similar in other respects to Figure 2 of the drawings.

30 The compressed gas release mechanism herein set forth has been designed to control the application of compressed gases to a pressure tank of a pressure tank sprinkler system. It is known that pressure tank sprinkler systems are used to furnish sprinkler protection to buildings located in areas where there is no city water supply available or where the city water supply is not dependable, and that such pressure tank sprinkler systems generally comprise a storage tank for the fire extinguishing fluid, which is connected to a sprinkler system which generally comprises a riser and a plurality of sprinklers positioned on suitable piping communicating therewith. Various means have heretofore been employed for causing the fire extinguishing fluid in the storage tank of the sprinkler system to be expelled from the tank through the sprinklers. The present invention relates to a specific form of pressure tank sprinkler system in which com-

40 pressed gas, preferably nitrogen, supplied in the conventional compressed gas cylinders commercially available, is used as the agent to apply pressure to the storage tank and force the fire extinguishing fluid therefrom. By referring to 45 the drawings and to Figure 1 in particular, it will be seen that a representation of a portion of a compressed gas cylinder is indicated by the numeral 10 and that the delivery end of the cylinder 10 is positioned partly within a lower portion of a housing 11 which housing encloses

the compressed gas release mechanism, which comprises a pair of guide rods 12 positioned vertically within the housing 11 and adapted to guide a weight 13 capable of vertical movement thereon and which weight 13 is normally suspended in elevated relation at the upper end of the guide rods 12 by means of a supporting finger 14 which is formed on a latch lever 15 which in turn is pivoted on a pivot 16 and which latch member 15 engages a portion of a pressure responsive weight releasing mechanism generally indicated by the numeral 17 which mechanism is the subject matter of Patent #2,099,069 of November 16, 1937, to E. A. Lowe et al., wherein its complete structure and principles are adequately set forth. In operation as described in the patent to Lowe et al., and in the present device, a partial rotation of the latch lever 15 about its pivot 16 comprises the complete movement upon which the activation of the gas release mechanism depends. As described in the above-mentioned patent to Lowe et al., the pressure responsive weight releasing mechanism 17 is constructed to be actuated on either an increase or decrease of pressure in air tubing, indicated by the numeral 18, which would normally communicate with a suction chamber such as is described in my heretofore referred to Patent 2,277,873 which suction chamber is affixed to and communicates with a riser of a sprinkler system. It will thus be seen that when certain actions occur in a sprinkler system and in parts associated therewith, a pneumatic impulse is delivered to the pressure responsive weight releasing mechanism 17 which in turn results in the movement of a pressure sensitive diaphragm in the said pressure responsive mechanism 17 which permits a partial rotation of a milled shaft 19 which in turn permits a lever 20 having a stop 21 formed thereon to move and, through a system of levers 22 and 23, also permits the latch lever 15 to rotate in a clockwise direction about its pivot 16 and thus permits the weight 13 to fall. It will thus be seen that, for example, a drop in the head of the liquid in a riser of the sprinkler results in a reduction of air pressure in the riser and in the subsequent reduction of air pressure in the air tubing 18 which communicates with the mechanism 17, thus actuating the same and causing the release of the various levers thereof so that the supporting finger 14 thereof may be moved downwardly as by the normal tendency of the weight 13.

The weight 13 is normally suspended on the supporting finger 14 through the medium of a suitable latch 24 which is suitably mounted on the said weight and which is normally held in operative position by means of a tension spring 25 which is attached to a depending portion of the latch 24 and to the weight 13. This latch structure permits the resetting of the weight 13 as the latch 24 will move out of normal position when it encounters the supporting finger 14 of the release mechanism 17 upon being reset. A slot 13A is formed in the weight 13 and is of sufficient width to clear the operating arm 29 so that the weight will not strike the operating arm 29 until the operating arm 29 reaches the top of the said slot 13A. The guide rods 12 terminate at their lower ends in suitable supporting brackets 12A provided with bumpers which are positioned at the sides of the lower central section of the compressed gas release mechanism housing 11 which mechanism includes a gear

segment 26 pivoted at a point 27 to the gas release mechanism housing 11. As is most clearly illustrated in Figure 2, this gear segment 26 is provided with a plurality of suitable gear teeth 28 and an outwardly and upwardly extending operating arm 29 which is positioned adjacent to and between the lower portions of the guide rods 12 so that the weight 13 upon its release by the pressure responsive weight releasing mechanism 17 will drop upon the arm 29 with a hammer-like blow, and thus cause the same to move the gear segment 26 partially about its pivot 27 in a clockwise direction so that the gear teeth 28 thereof suitably rotate a toothed gear 30 which in turn, is affixed to a control valve 31 of the compressed gas cylinder 10 which extends, as may be seen in Figure 1, into the lower central portion of the release mechanism housing 11. It will thus be observed that the actuation of the pressure responsive weight releasing mechanism 17 results in the drop of the weight 13 and the partial rotation of the gear segment 26 about its pivot 27 with the simultaneous opening of the control valve 31 of the compressed gas cylinder 10:

In order that the compressed gas thus released from the cylinder 10 may be directed into a pressure tank of an associated pressure tank sprinkler system, a suitable coupling 32 and a conventional pressure regulator 33 are positioned in the lower portion of the gas release mechanism housing 11, the coupling 32 being adapted to establish a suitable connection between the pressure regulator 33 and the compressed gas cylinder 10 by way of the control valve 31 thereof. Suitable tubular connections 34 connect the pressure regulator 33 with the pressure tank of the pressure tank sprinkler system so that the released gases may enter thereinto and force the fire extinguishing fluid therefrom.

In order that a desirable signal may be given upon the actuation of the release mechanism in the housing 11, a suitable electrical switch is incorporated in the structure thereof and is indicated in Figures 1 and 2 by the numeral 35. A projecting arm 36 of the switch 35 is depressed by the weight 13 when the same is dropped thus effectively establishing an electrical circuit through the switch 35 which may be used to energize an alarm signal.

The compressed gas release mechanism enclosed in the housing 11 and the compressed gas cylinder 10 are preferably mounted upon the pressure tank of the pressure tank sprinkler system by means of suitable mounting brackets and it will be obvious that some of these mounting brackets may be employed to position and support the compressed gas cylinder 10 upon the pressure tank of the pressure tank sprinkler system and in operative relationship to the release mechanism hereinbefore described. In addition thereto, adjusting screws 37 are provided so that the cylinder 10 may be moved thereby into proper alignment with respect to the gas release mechanism in the housing 11. These adjusting screws also serve to properly align the neck and valve portions of the gas cylinder 10 with the gear segment 26 of the release mechanism. In addition thereto a supporting arm 38 engages the valve stem of the control valve 31 of the compressed gas cylinder 10 to insure its accurate and dependable support and positioning with respect to the gear segment 26. It is obvious that the toothed gear 30 is substituted

for the conventional hand wheel commonly supplied with compressed gas cylinders.

By referring to Figures 1 and 2 of the drawings, it will be seen that a cover portion 39, the majority of which has been broken away in the illustration, is provided to suitably enclose the mechanism and the cover 39 serves to maintain in non-operating position a safety latch 40 which is pivoted by means of a pivot 41 to the housing 11 of the gas release mechanism. As may be seen in Figure 1 of the drawings, this safety latch 40 comprises a U shaped member pivoted at its lowermost portion to the housing 11 so that upon removal of the cover 39 the safety latch 40 will tend to move into effective operating position as shown in Figure 1, so that an actual release of the weight 13 will not result in the movement of the gear segment 26 due to the weight's striking an upwardly projecting portion 42 of the safety latch 40. When the cover 39 is in position the safety latch 40 is effectively moved into non-operative position (not shown), so that the upwardly projecting portion 42 thereof will not engage the weight 13 and this will in no way interfere with the operation of the gas release mechanism. The safety latch is provided so that the gas release mechanism in the housing 11 may be opened and tested from time to time without actually releasing the gas from the cylinder 10 to the pressure tank of the sprinkler system as would otherwise be the case. Due to its U-shaped form and the fact that the pivot 41 is off center with respect to the latch proper, the safety latch's normal tendency is to move outwardly of the release mechanism upon the removal of the cover 39 thus bringing the upwardly projecting portion 42 thereof into effective position for blocking the complete dropping of the weight 13, as shown in Figure 1.

By referring to Figure 4 of the drawings a modified form of gas release mechanism may be seen wherein certain portions of the device heretofore described are eliminated and an electric motor substituted, the electric motor being indicated in the drawings by the numeral 44, a shaft 45 of which is coupled directly, preferably by means of a set screw, to a gear segment 46 which is similar in all respects to the gear segment 26 heretofore described and which is adapted to engage a toothed gear 47 positioned on and forming a part of a control valve 48 of a compressed gas cylinder 49. A support arm 50 supports the valve stem of the control valve 48 and in this modification as in the other form of the invention it is obvious that the toothed gear 47 is substituted for the hand wheel normally supplied with compressed gas cylinders. The gas, upon being released due to the partial rotation, by the motor 44, of the gear segment 46 engaging the toothed gear 47, flows through a coupling 51 and through a conventional regulator 52 and leaves the compressed gas release mechanism by means of a tube 53 which passes through an opening in the housing 54 positioned about and forming an enclosure for the mechanism. The tube 53 communicates with a pressure tank of a sprinkler system.

The housing 54 and the mechanism therein, is preferably mounted upon the pressure tank by means of suitable brackets and it will be obvious that the electric motor 44 must be of a type having a high initial starting torque in order to move the gear segment 46 and thus rotate the toothed gear 47 of the control valve 75

48. In order that the electric motor 44 may be controlled a supply line thereto is indicated by the numeral 55 and it will be observed that a switch 56 is cut into the supply line 55 by means of a pair of wires 57 which switch is disposed above the gear segment 46 in a position so that the gear segment upon completing the opening of the control valve 48 will rise into engagement with the switch 56 and cause the same to open and break the circuit and thus disconnect the electric motor 44.

As these devices must be manually reset and a new tank of gas supplied after each operation, the electric circuit to the motor will, therefore, remain broken until the gear segment is moved downwardly and the entire device reset for another operation.

It will be obvious to those skilled in the art that other modifications of this invention are possible and desirable under certain conditions one of which modifications would comprise the simple substitution of an electric actuated and controlled solenoid positioned in place of the pressure responsive release mechanism 17 and thereby controlling the suspended weight 13. By referring to Figure 5 of the drawings, it will be seen that a modified form of the compressed gas release is illustrated wherein the release device as heretofore described and illustrated in Figures 1 and 2 is adapted for electrical operation by the substitution of an electrically controlled and actuated solenoid 59. The solenoid 59 is mounted in operable manner within an enclosure 60 which compares in detail with the space occupied by the pneumatic gas release mechanism 17 heretofore described. The enclosure 60 is formed within the upper portion of a compressed gas release mechanism housing 61 in which the delivery end 62 of a compressed gas cylinder is positioned. The compressed gas release mechanism comprises a pair of guide rods 63 positioned vertically within the housing 61 and adapted to guide a weight 64 capable of vertical movement thereon and which weight 64 is normally suspended in elevated relation on the upper ends of the guide rods 63 by means of a supporting finger 65 which is formed on a latch lever 66 which in turn is pivoted to the housing 61 by means of a pivot 67. An upwardly extending portion of the latch lever 66 is adapted to be releasably retained beneath a keeper 68 formed on a trigger member 69 which in turn is pivoted to the housing 61 by means of a pivot 70. A downwardly and sidewardly extending portion of the trigger member 69 extends beneath the solenoid 59 so that the operative portion 71 of said solenoid is normally engaged in a groove 72 in the trigger member 69. It will be observed that the weight 64 is suspended in elevated relation on the guide rod 63 by means of the supporting finger 65 which is normally held in stationary position by the keeper 68 of the trigger member 69 which in turn is normally restrained by the operating portion 71 of the solenoid 59. Actuation of the solenoid 59 causes the upward travel of the operating member 71 which in turn releases the trigger member 69 thus permitting the weight 64 which rests upon the finger 65 to swing the trigger member 69 outwardly and to rotate the latch lever 66 in a clockwise direction thereby removing the support from beneath the weight and permitting it to fall. The weight 64 in falling is directed by the guide rods 63 into engagement with an operating arm 73 which is formed upon a

gear segment 74 which is pivoted by means of a pivot 75 to the housing 61 in a manner so that upon being struck and moved by the weight 64 the gear segment 74 will rotate a toothed gear 76 positioned on the valve stem normally associated with the delivery end 62 of a compressed gas cylinder. The rotating motion imparted to the toothed gear 76 revolves the valve stem, opens the valve and releases the compressed gas which is directed to its point of use by means of a coupling 77 and, if desired, a conventional pressure regulator 78. It will be observed that most of these operating portions of the compressed gas release mechanism are exactly the same as heretofore described and illustrated in Figure 2 of the drawings. In order to actuate the solenoid 59 or for that matter the electric motor 44 in Figure 4 of the drawings, electrical thermostats such as are commonly known in the art are employed. In Figure 5 a suitable electrical thermostat and/or a system of such thermostats and any relay mechanisms necessary are electrically connected to the solenoid 59 by suitable electrical connections (not shown) which are well known in the art. It will thus be seen that the modified form of the compressed gas release mechanism is subject to electrical control by electrical thermostats and which mechanism will upon actuation cause the weight 64 to be dropped which will impart a hammer-like blow to the gear segment 72 which in turn will revolve the valve of the compressed gas tank upon which valve the gear 76 is positioned and result in the immediate and satisfactory release of the compressed gases.

Having thus described my invention, what I claim is:

1. A compressed gas release mechanism adapted to release compressed gases from a gas cylinder equipped with a rotatable control valve, the said release mechanism comprising a weight, a weight operated lever positioned in operative relation to the rotatable control valve of the said gas cylinder, and including structural means for suspending the weight above the said lever and means for dropping the said weight so as to open the rotatable control valve and release the compressed gases from the said gas cylinder.

2. In a release mechanism adapted to release compressed gases from a compressed gas source, a release weight, a latch carried by said release weight, remotely controlled means for releasing the said weight and including a supporting element engageable beneath the said latch, a control valve for the said compressed gas source, a motion transmitting member positioned beneath the said release weight and adapted to be moved thereby as upon the weight's falling, the said motion transmitting member engaging a gear on the said control valve and adapted to open the valve by means of the movement imparted thereto by the said weight.

3. In a release mechanism adapted to release compressed gases from a compressed gas source, a release weight, a latch carried by said release weight, remotely controlled means for releasing the said weight and including a supporting ele-

ment engageable beneath the said latch, a control valve for the said gas source, a gear segment having an arm positioned beneath the said release weight and adapted to be moved thereby upon the weight's falling thereon, the said gear segment operatively engaging a gear secured to the said control valve so that movement imparted to the gear segment by the said weight opens the said control valve and releases the compressed gas from the compressed gas source.

4. A compressed gas release mechanism adapted to release compressed gases into a pressure tank of a sprinkler system, the said compressed gas releasing mechanism comprising a housing, guide means positioned in said housing, a weight capable of vertical movement positioned on the said guide means, a weight releasing mechanism positioned in the said housing and adapted to suitably suspend the said weight, an opening in the lower portion of the said housing adapted to permit the entrance thereinto of the valve portion of a compressed gas cylinder, a gear affixed to the said valve and a gear segment pivoted to the said housing and engaging the said valve gear, an arm formed on the said gear segment adapted to engage the said weight in falling so that the said valve may be opened thereby.

5. In a compressed gas release mechanism the combination of a weight releasing mechanism and an actuating weight suspended thereby, a gear segment, a weight engaging arm formed thereon and positioned so that the said actuating weight in falling will move the said gear segment, a compressed gas source including a control valve, a gear affixed to the said control valve and engaging the said gear segment, so that movement of the said gear segment in response to the falling weight opens the said control valve and releases compressed gases from the said compressed gas source.

6. A compressed gas release mechanism adapted to release compressed gases into a pressure tank of a sprinkler system, the said compressed gas releasing mechanism comprising a housing, guide means positioned in said housing, a weight capable of vertical movement positioned on the said guide means, a weight releasing mechanism positioned in the said housing and adapted to suitably suspend the said weight, the said weight releasing mechanism comprising a latch lever having a weight supporting finger formed thereon, a trigger member normally restraining the movement of the said latch lever and an electrically actuated solenoid normally restraining movement of the said trigger member, an opening in the lower portion of the said housing adapted to permit the entrance thereinto of the valve portion of a compressed gas cylinder, a gear affixed to the said valve and a gear segment pivoted to the said housing and engaging the said valve gear, an arm formed on the said gear segment adapted to engage the said weight in falling so that the said valve may be opened thereby.

HARRY N. RIDER.
